TOY

Thomas R. Bush, McKenzie, Tenn.

Application June 5, 1944, Serial No. 538,747

2 Claims.

(Cl. 46—101)

This invention relates to toys of the mechanical toy type, and the object of the inventor is to produce a toy with an oscillating platform which is alternately inclined and on which a wheeled figure, here shown as a wheelbarrow, is seemingly propelled by a walking figure simulating a toy man; the movement of these figures being accomplished by gravity on the inclined surface of the platform the inclination of which is successively changed as the moving figures reach the ends of the platform; and the invention furthermore includes mechanically operated means for successively elevating the ends of the platform at locations at the sides of a fulcrum on which the platform is oscillatable.

It is a further object of the invention to provide mechanical toys or objects at the ends of the platform which are successively raised or elevated as the platform is manipulated, one such figure having articulating arms associated with means for oscillating the arms in order that they may engage a portion of the wheeled object and give impetus to the toy, of such a nature as to insure the initial movement of the toy down the inclined surface of the platform; and the invention furthermore includes the provision of a simulated toy man having an articulated leg and foot which is likewise operated successively with the figure at the other end of the platform to give initial movement to the wheeled toy or parts associated with it.

It is a still further object of the invention to provide a toy which will be hereinafter referred to as the "walking toy," that is the one associated with the wheeled portion of the movable objects, with articulated legs which alternately swing in step-like motions as it advances on the platform, and to associate therewith, novel means for regulating the length of step or stride afforded the simulated legs of the toy in order that its progress or motion may be curtailed; means being also provided for the manual manipulation of the aforesaid regulating instrumentality.

It is furthermore an object of the invention to provide a platform mounted for oscillation in the manner of a seesaw, novel means being provided for supporting the platform on a base, and to provide means associated with the base and the articulating members of the toys at the ends of the platform whereby they are automatically moved as the ends of the platform ascend, it being understood that the parts are returned to normal positions by gravity when the ends of the platform on which they are mounted descend.

With the foregoing and other objects in view, the invention consists in the details of construction, and in the arrangement and combination of parts to be hereinafter more fully set forth and claimed.

In describing the invention in detail, reference

will be had to the accompanying drawings forming part of this application, wherein like characters denote corresponding parts in the several views, and in which:

Figure 1 illustrates a view in elevation of a toy embodying the invention;

Figure 2 illustrates a plan view thereof;

Figure 3 illustrates a sectional view of the toy on the line 3—3 of Fig. 2, omitting the figures;

Figure 4 illustrates a sectional view on the line 4—4 of Fig. 2, omitting the figures;

Figure 5 illustrates a detail view in elevation showing a fragment of the base and platform, and a figure at one end of the platform;

Figure 6 illustrates a sectional view approximately on the line 6—6 of Fig. 5;

Figure 7 illustrates a view in elevation of the rear of the figure shown in Figures 5 and 6;

Figure 8 illustrates an enlarged detail view of the figure at the opposite end of the platform;

Figure 9 illustrates a sectional view on the line 9—9 of Fig. 8;

Figure 10 illustrates a view in rear elevation of the said figure;

Figure 11 illustrates a view in side elevation of the walking figure of the toy;

Figure 12 illustrates a sectional view on the line 12—12 of Fig. 11;

Figure 13 illustrates a sectional view on the line 13—13 of Fig. 11;

Figure 14 illustrates a sectional view on the line 14—14 of Fig. 13;

Figure 15 illustrates a sectional view of the toy on the line 15—15 of Fig. 14;

Figure 16 illustrates a sectional view of the toy on the line 16—16 of Fig. 14; and

Figure 17 illustrates a sectional view of the toy on the line 17—17 of Fig. 14.

In these drawings 20 denotes a base which is in the nature of an elongated board, or the like, having recesses 21, through which recesses pintles 22 extend, and into which recesses tongues 23 are partially rotated on the pintles 22, said pintles extending through appropriate apertures of the tongues; and the said tongues are integral with a cross-piece 24 attached to the under surface of a platform 25 which oscillates so that its ends are successively raised and lowered in the manner of a seesaw. The cross-piece is attached to the platform in appropriate manner by fastenings 26 such as screws, nails or the like.

At a suitable distance between the cross-piece and the ends of the platform, means are provided for alternately lifting or raising the ends of the platform and, as here shown, the said means each comprises a length of metal bent to form a central crank 27 with the parts of the metal integral with the cranked portion forming journals, as at 28, that are partially rotatable on the upper surface of the base and are held in place by fas-

tenings, such as staples 29, which permit the partial rotation of the journals. The outer end of the length of material is formed into a handle 30 that is manipulated to elevate the crank to the position in which it is shown in Figure 4, or to a position parallel with the upper surface of the base, so that by the alternate manipulation of these two devices which are under the platform, the said platform is moved to inclined positions and held until they are further manipulated. Near each end of the platform a batten 31 is anchored and it acts as an abutment or stop to the movement of the wheeled toy which travels down the platform when it is in an inclined position.

In the present illustration, the traveling toy comprises a simulated wheelbarrow 32 having handles 33 and a supporting wheel 34, and the wheelbarrow may be illustrated as appropriately loaded with material to be transported. The walking figure 35 of the traveling toy has a simulated body 36, with simulated depending arms 37, and in the space between the arms, the upper ends of the legs 38 are oscillatably mounted on a pintle 39. The oscillatory movement of the legs in one direction is limited by a cross-brace 40 extending through the arms and across the space where the legs oscillate, and on the opposite side the oscillatory movement of the legs is controlled by a depending plate or apron 41 which is slideable vertically of the figure under the influence of a rod 42 that extends through the top of the figure and has a knob by which it may be grasped by an operator for manipulating the rod and controlling the position of the apron. When the apron is lowered, the forward movement of the legs will be restricted as compared with the movement allowed them when it is elevated, this being clearly apparent from an inspection of Fig. 14.

The handles 33 of the wheelbarrow are lodged in recesses 43 at the ends of the simulated arms and are held therein by metal staples 44 which have horizontal portions extending through the arms and depending portions anchored in the handles, thus creating a strong and durable joint between the simulated arms of the toy, and the said handles. Simulated feet 45 are mounted on the ends of the legs and they have relatively broad areas at the bottom, as at 46, where they contact the platform and their faces or surfaces may be slightly beveled toward the ends to facilitate the walking movement. A spacing ring 47 is applied to the pintle 39 between those portions of the legs which are mounted on the pintle and it serves to hold the legs in proper position and obviates friction.

The figures 48 and 49 at the ends of the platform are stationarily mounted through the employment of anchoring pins such as 50, and the figure 48 has one of its legs 51 oscillatively mounted on a pivot 52. The said leg 51 has a simulated shoe 53 on its end and when the leg is moved or swung outwardly as shown in Fig. 5, it will strike an end of the wheelbarrow handle and serve to give impetus to the wheeled toy. It is seen that the swinging movement of the leg 51 is occasioned by the flexible connection or chain 54 which has one end anchored to an eye 55 attached to the leg 51, and its opposite end anchored as at 56 to the base, it being understood that as the end of the platform on which the figure 48 is lowered or de-

pressed, the leg will descend by gravity to its normal position.

The figure 49 has oscillatable arms 57 mounted on a pivot 58 and these arms are connected together above the pivot by links 59, to the inner ends of which links a flexible member or chain 60 is attached, and the said flexible member or chain has its opposite end anchored to the base as at 61. Hence, the assembly disclosed causes the actuation of the arms from their full line positions shown in Figs. 8, 9 and 10 to the dotted line position in which the parts are shown in Fig. 8, and the relation of parts is such that as the arms are moved upwardly, they encounter the ends of the handle of the wheelbarrow and give initial impetus to the movable toy; it being understood that when the wheelbarrow has reached the abutment at the end of the platform it will be arrested by the batten 31 and may then be reversed as to position so that it will be travelling in a direction opposite to that in which it is shown in Fig. 1 after the platform has been appropriately adjusted to change its inclination.

With further reference to Figures 13 and 14, it is seen that the plate 41 has edge surfaces 41^a which are engaged by pins 41^b which serve to brace the said plate at its rear, and that the plate is engaged on its front surface by a rod 41^c so that it is held in position against the action of the legs which might strike it. The rear surface of the plate is provided with recesses 41^d which affords a clearance for the free movement of the legs during their oscillation.

I claim:

1. In a toy, a base, a platform having a fulcrum supported by the base, means on the base at either side of the fulcrum for alternately raising and supporting the platform in inclined positions,

40 a mechanical figure at each end of the platform having articulating elements, a member anchored to the base at each end and connected to an articulating element on the adjacent end of the platform, and a perambulating figure movable on the inclined surface of the platform, the said perambulating figure being initially impelled by the figure at either end of the platform and kept in motion by gravity.

2. In a toy, a base, a platform having a fulcrum supported by the base, means on the base at either side of the fulcrum for alternately raising and supporting the platform in inclined positions, a mechanical figure at each end of the platform having articulating elements, a member anchored to the base at each end and connected to an articulating element on the adjacent end of the platform, a perambulating figure movable on the inclined surface of the platform, the said perambulating figure being initially impelled by the figure at either end of the platform and kept in motion by gravity,

55 a perambulating figure comprising a wheeled carrier and a simulated person by which a portion of the carrier is supported, the said simulated person comprising a body and articulating legs oscillatably mounted thereon, the said legs terminating in simulated feet which advance step-by-step on the platform.

THOMAS R. BUSH.
